DESIGN FOR A FISHING POLE

Thomas R. Blando, Utica, N. Y.

Application April 17, 1944, Serial No. 113,288

Term of patent 14 years

(Cl. D31—4)

To all whom it may concern:

Be it known that I, Thomas R. Blando, a citizen of the United States of America, residing at Utica, county of Oneida, and State of New York, have invented a new, original, and ornamental Design for a Fishing Pole, of which the following is a specification, reference being had to the accompanying drawing, forming a part thereof, wherein the figure is a perspective view of a fishing pole, showing my new design.

I claim:

The ornamental design for a fishing pole, as shown.

THOMAS R. BLANDO.
